TOOL BRACKET AND INDEXING ASSEMBLY

Stanford P. Bruce, Detroit, Mich., assignor to
Wheel Trueing Tool Company, Detroit, Mich.,
a corporation of Michigan

Application October 26, 1948, Serial No. 56,500

5 Claims. (Cl. 125—11)

1

This invention relates to a tool bracket assembly. More particularly, the invention relates to a bracket assembly and mounting for a pawl to be used in conjunction with a ratchet wheel for automatically effecting a periodic rotation of a diamond dressing tool.

In my copending application, Serial No. 744,749, filed April 29, 1947, entitled "Grinding Wheel Dressing Mechanism," I have described a mechanism for trueing the surfaces of abrasive wheels in which a tool holder is subjected to periodic rotation so that the diamond point of a diamond dressing tool is worn uniformly and presents a sharp cutting edge to the wheel at all times.

The present tool bracket is particularly suitable for use in connection with a device of the type disclosed in my aforementioned copending application, but has general applicability to pawl and ratchet assemblies.

An object of the present invention is to provide a tool bracket assembly having a pawl member capable of being adjusted into proper operating position for engaging a ratchet.

Another object of the invention is to provide a pawl assembly particularly adapted for use in conjunction with a ratchet-actuated grinding wheel dressing tool.

In general, the tool bracket of the present invention comprises a mounting plate, an arm pivotally secured to one end of the plate, a cross member pivotally secured to both the mounting plate and the adjusting arm, a pawl pivotally attached to the cross member and a stop on the cross member for limiting the swinging arc of the pawl.

A more detailed description of the assembly of the present invention will be made in connection with the discussion of the drawings.

On the drawings:

Figure 1 is an end elevational view of a conventional grinding machine with a portion of the guard broken away and in section to show the mounting of the tool bracket of the present invention.

Figure 2 is an end elevational view of the tool bracket of the present invention.

Figure 3 is an enlarged vertical sectional view taken substantially in the plane of the axis of the tool holder, showing the tool bracket and wheel dressing mechanism in cooperating relationship to rotate the diamond dressing tool at an end of its traverse across the face of the grinding wheel.

Figure 4 is a fragmentary, sectional view taken substantially along the line IV—IV of Figure 3,

2

and showing in dotted lines the pawl swung in its inoperative position.

As shown on the drawings:

In Figure 1, reference numeral 10 denotes in general a conventional grinding wheel partially shielded by means of a guard 11. Behind the guard 11, a bed 12 supports a slide 13 for traversing movement parallel to the axis of rotation of the grinding wheel 10. Associated with the slide 13 is a tool holder 14 which carries a diamond dressing tool 15 having a diamond point 15a for use in trueing the grinding wheel 10. The tool 15 is rotatable by rotation of a ratchet wheel 16 fixedly mounted with respect to the tool. The ratchet wheel 16 is actuated by engagement with a pawl 20 which forms a part of a bracket assembly including a mounting plate 17, an adjustable arm 18, and a cross member 19.

The mounting plate 17 (Figure 2) is slotted 20 as at 17a and 17b to receive bolts 36 and 37 for securing the assembly in operating position on the guard 11 of the grinding wheel assembly. Attached to the mounting plate 17 is an adjusting arm 18 which is composed of a slotted channel member 21 and a slide arm 22 carrying a locking screw 23 adapted to secure the slide arm 22 at any point within the length of slot 21a of channel member 21. The adjusting arm 18 is pivotally secured to the mounting plate 17 by means of a U-shaped bracket 24 which is secured to the mounting plate 17 by means of rivets 25 and 26 and is secured to the adjusting arm 18 by means of an Allen type screw 27. An offset flange portion 19a (Figures 2 and 3) is formed 35 on the cross member 19 to act as a stop to limit the swinging movement of a pawl member 20. The pawl member 20 consists of an elongated bar 27 and a ratchet-actuating member 28 secured to the bar 27 by means of rivets 29.

The pawl mechanism 20 is pivotally mounted 40 to the cross member 19 by means of screws 41 and 42 provided with adjusting nuts 43 and 44. The pawl mechanism is thus freely swingable about the axis of screws 41 and 42, except as limited by the stop 19a.

In operation, as the slide 13 carrying the diamond dressing tool nears the end of its traverse in one direction across the face of the grinding wheel and the point 15a is out of contact with 50 the surface of the wheel, as shown in Figure 3, the ratchet wheel 16 comes into contact with the ratchet-actuating member 28 of the pawl 20. Since the pawl 20 is held rigidly in vertical position against rotational movement in the direction of the slide by means of the stop 19a, the

ratchet wheel 16 is rotated, and with it the tool 15, through an angle equal to the angular spacing of the teeth of the ratchet wheel. Upon reversal of the direction of movement of the slide 13 to begin another traverse of the grinding wheel, the pawl 20 rides freely over the teeth of ratchet wheel 16 by virtue of its being freely pivoted from the cross member 19, as illustrated in the dotted lines of Figure 3. The angularity of its sloping face 28a facilitates the movement of the pawl 28 over the ratchet teeth during this reverse movement of the slide.

The tool holder 14, as best shown in Figure 3, comprises a body portion 30 having a shank 30a held against rotation in the assembly by means of a screw 31 engaging a notch 30b formed in the shank 30a. The body member 30 is internally bored as at 30c to rotatably mount the pilot 32a of a tool adapter 32. A radially extending flange adapter portion 32b formed on the tool adapter 32 is adapted to be seated against a bearing surface 30d formed in the body member 30, and is urged thereagainst by means of a collar 33 acting upon a resilient spring washer 34 and a washer 35. The tool adapter 32 which carries the diamond tool 15 is thus held axially under a resilient thrust that eliminates chattering while permitting rotation of the tool.

It will be noted that whenever it becomes necessary, the pawl assembly can be adjusted to align the pawl member 20 with the ratchet wheel 16. This is done by loosening screws 27, 32, 39 and screw 23 in the sliding arm 22 within the channel 21 until the appropriate angle is achieved, and thereupon the screws 23, 27, 32 and 39 are tightened to lock the arm in its adjusted position.

A distinct advantage of the present invention lies in the fact that the tool bracket may be disassembled for the purpose of mounting a new grinding wheel and reassembled without changing the setting of the adjusting arm 18. This is accomplished by keeping screws 23 and 38 tightened in place, and removing screws 27 and 39, thus permitting the assembly to be disassembled and reassembled without changing the angular relationship between the arm 18 and the cross member 19.

While I have shown a particular embodiment of my invention, it will, of course, be understood that I do not wish to be limited thereto since many modifications may be made, and I, therefore, contemplate by the appended claims to cover all such modifications as fall within the true spirit and scope of my invention.

I claim as my invention:

1. A tool bracket comprising a mounting plate, an arm adjustable in length secured to one end of said plate, a cross member pivotally secured at its ends to said plate and said arm respectively, said cross member having an offset flange portion projecting therefrom, and a pawl pivotally secured to said cross member for pivotal movement about an axis parallel to said cross member and having its pivotal movement in one direction limited by said offset flange portion while free to move in the opposite direction.

2. A pawl assembly comprising a mounting plate, an arm adjustable in length being releasably secured to said plate, a cross member pivotally secured to both said plate and said arm, a pawl pivotally mounted on said cross member for free swinging movement thereabout, and stop means intermediate the ends of said cross member extending into the path of swinging move-

ment of said pawl for preventing swinging movement of said pawl in one direction.

3. A pawl assembly comprising a mounting plate, an arm of adjustable length secured thereto, a cross member pivotally secured to said mounting plate and said adjustable arm, a pawl depending from said cross member for limited swinging movement relative thereto, and stop means intermediate the ends of said cross member extending into the path of swinging movement of said pawl for preventing swinging movement of said pawl in one direction from the vertical.

4. In combination, a rotatable abrasive wheel, a guard shielding said wheel, a tool rotatable about its axis and freely extending through said guard into operative relation with said wheel, means operatively connected to said tool for reciprocating said tool to cause the same to traverse the surface of said wheel, said tool having a ratchet wheel thereon for periodically indexing said tool at the completion of a traverse of said tool across the surface of said grinding wheel, a pawl assembly arranged to rotate said ratchet wheel, said pawl assembly comprising a mounting plate secured to said guard, an arm adjustable in length removably secured to said plate, a cross member pivotally and removably secured both to said plate and to said arm, a pawl mounted for swinging movement about said cross member and positioned to engage said ratchet wheel upon the completion of a traverse of said tool across the surface of said wheel, and stop means intermediate the ends of said cross member for limiting the arc through which said pawl may be swung.

5. In a grinding wheel dressing assembly having a rotatable abrasive wheel, a guard shielding said wheel, a dressing tool rotatable about its axis and freely extending through said guard into operative relation with said wheel, means operatively connected to said tool for reciprocating said tool to cause the same to traverse the surface of said wheel, said tool having a ratchet wheel thereon for periodically indexing said tool at the completion of its traverse across the surface of said grinding wheel, a pawl assembly adapted to rotate said ratchet wheel, said pawl assembly comprising a mounting plate secured to said guard, an arm adjustable in length pivotally and removably secured to said plate, a cross member pivotally and removably secured to both said plate and said guard, a pawl mounted for free swinging movement about said cross member and positioned to engage said ratchet wheel at the completion of a traverse of said tool across the surface of said abrasive wheel, and an offset flange on said cross member for limiting the arc through which said pawl may be swung.
